UNITED STATES PATENT OFFICE.

CLARENCE H. DOOLEY, OF ROCK ISLAND, ILLINOIS, ASSIGNEE TO DEERE & MANSUR CO., OF MOLINE, ILLINOIS, A CORPORATION OF ILLINOIS.

MARKER MECHANISM FOR PLANTERS.

1,142,314.

Specification of Letters Patent.

Patented June 8, 1915.

Application filed August 6, 1912. Serial No. 783,424.

To all whom it may concern:

Be it known that I, CLARENCE H. DOOLEY, a citizen of the United States, residing at Rock Island, in the county of Rock Island 5 and State of Illinois, have invented certain new and useful Improvements in Marker Mechanism for Planters, of which the following is a specification, reference being had therein to the accompanying drawing.

My invention relates more particularly to improvements in marker mechanisms of the disk type, and the object is to provide improved means for mounting the disk on the pole and for adjusting it.

15 Of the accompanying drawings which illustrate one embodiment of my invention—Figure 1 is a plan view of a planter having a marker mechanism embodying my invention; Fig. 2 is a front view of the planter, the forward parts being omitted for the sake of clearness; Fig. 3 is a fragmentary 20 sectional view through the marker pole and disk and the connecting devices.

Referring to the drawings 1 represents as 25 a whole the planter frame which is mounted upon the ground wheels 2—2 and the axle 3.

4—4 are seeder mechanisms mounted upon the frame in advance of the wheels.

5 is a marker pole carrying at its end a 30 marker disk 6 rotatably mounted at an angle to the pole axis. The inner end of the pole is pivotally secured to a rearward extending bracket 7, and a link 8 is provided for connecting the pole to the frame at either side.

35 The operator, by disconnecting the inner end of the link, can swing the pole from one side to the other and can then again fasten the link in place.

By referring to Fig. 3 it will be noted that 40 the disk 6 is mounted on a journal casting or holder 9 which has an arm or bracket 10 extending along the pole at one side. A bolt 11 passes through the pole and the arm and holds the casting in place. In order that 45 the holder may be adjusted angularly on the pole to change the angle of the disk, a casting 12 is provided. This is provided at 13 with a slot through which passes a bolt 14 for securing it in place. The end of the 50 casting 12 is beveled at 15 and this beveled or wedge shaped end can be inserted under the bracket 10 of the holder 9, the bolt 11 being loosened. By adjusting the wedge casting 12 the angle of the disk can be 55 changed, and when the desired adjustment

is attained, the parts can be locked in place by means of the bolts.

It will be observed that there are several holes for the bolts 11 and 14. These make possible the adjustment of the marker longitudinally of the pole. These holes in the pole are uniformly spaced so that any two adjacent ones can be used for receiving the two bolts 11 and 14.

What I claim is:

1. In a corn planter marking device, the combination of a non-rotatable pole straight from end to end, a non-rotatable disk holder having an inward projecting bracket open on one side and extending along the pole, 70 a concavo-convex disk rotatably mounted on the holder and held thereby when in operation in fixed angular relation to the ground, a fastening device positively holding the bracket and disk in fixed relation to the 75 pole axially and angularly, and means interposed between the bracket and the pole for varying the angle with respect to the pole at which the bracket and disk are held by the said fastening device. 80

2. In a corn planter marking device, the combination of a non-rotatable pole straight from end to end, a non-rotatable disk holder having an inward projecting bracket open on one side and extending along the pole, a 85 concavo-convex disk rotatably mounted on the holder and held thereby when in operation in fixed angular relation to the ground, a fastening device holding the bracket and disk in fixed relation to the pole axially and 90 angularly, and a wedge interposed between the bracket and the pole and adjustable along the pole for varying the angle with respect to the pole at which the bracket and disk are held by the said fastening device. 95

3. In a corn planting marking device, the combination of a non-rotatable pole straight from end to end and having three or more equally spaced transverse bolt holes there-through near the outer end, a non-rotatable 100 disk holder having an inward projecting bracket open on one side and extending along the pole, a concavo-convex disk rotatably mounted on the holder and held thereby when in operation in fixed angular relation to the ground, a bolt adapted to extend through any of the aforesaid holes to positively hold the bracket and disk in fixed 105 relation to the pole axially and angularly in any of several positions of longitudinal ad- 110

justment, a slotted wedge adapted to be interposed between the bracket and the pole at any one of the said positions for varying the angle with respect to the pole at which the bracket and disk are held by the said bolt, and a second bolt adapted to extend through the slot in the wedge and the hole in the pole immediately adjacent the one

containing the first said bolt for holding the wedge in adjustable position.

In testimony whereof, I affix my signature, in presence of two witnesses.

CLARENCE H. DOOLEY.
